Atty.

UNITED STATES PATENT OFFICE.

GEORGE WILLIAM HARRISON, OF LONDON, ENGLAND, ASSIGNOR TO G. R. BALDOCK & CO. LIMITED, OF LONDON, ENGLAND, A COMPANY OF GREAT BRITAIN.

EXPANDING BRACELET, BELT, OR THE LIKE.

Application filed August 9, 1921. Serial No. 480,957.

To all whom it may concern:

Be it known that I, GEORGE WILLIAM HARRISON, a subject of the King of Great Britain and Ireland, residing at 7 Northampton 5 Square, London, E. C. 1, England, have invented new and useful Improved Construction of Expanding Bracelet, Belt, or the like, of which the following is a specification.

This invention relates to the class of expanding bracelet, belt or the like in which each unit comprises two superimposed cases carrying springs and two pairs of side plates or frames positioned outside the superimposed cases and having cross pins positioned 10 within the superimposed cases and adapted to compress the springs in their respective cases in opposite directions, the remote ends of the respective side plates or frames being connected to the corresponding side plates 15 of the next link by connecting links.

My present invention consists in constructing such class of spring controlled expanding bracelet, belt or the like wherein each expanding link slides within the outer 25 edge of the main link or case and is retained and guided by turned over edges thereof, the upper sliding link of each expandable unit being connected to the lower link of the next expandable unit.

My invention will be clearly understood 30 from the following description aided by the accompanying drawings in which—

Figure 1 is a side sectional elevation, Figure 2 a longitudinal section on the line 2—2 of Figure 1 and Figure 3 a section on the 35 line 3—3 of Figure 1, of a spring link constructed according to my invention the attachment at the ends being shown for connection to another link and for connection 40 to a watch.

Figure 4 is a side elevation of a top sliding link and showing the means at the end for connection to the next link.

Figure 5 is a side elevation of a bottom 45 sliding link for connection to a watch.

Figure 6 is a side elevation of a top link provided with means for connection to a top sliding link of the next link the two links being positioned at the centre of the 50 bracelet.

Figure 7 is a plan of a sliding link for use with very wide bracelets and in which it is advisable to use two springs for each sliding link.

Figure 8 is a plan of a bracelet slightly 55 opened out.

Figure 9 is a side elevation of a bracelet.

Figs. 10 and 11 are opposite end views respectively of the main link.

I construct each ordinary link A with 60 open sides and closed ends and within such link A I position centrally a wall B running from end to end and across from one side to the other, such wall being securely held to the ordinary link. 65

Each sliding link C, D consists of two bars connected at their ends. To one end of each top sliding link C except the two central sliding links hereafter described, I fix a hinge joint E, this joint preferably 70 consisting of a piece of metal in the form of the figure 3 in section, the upper half of this hinge joint being soldered to the link C shown at Figure 4.

The bottom links D are constructed the 75 same as the top links C but without the fastening device except the two end bottom links which are provided with upturned lips F between which is pivoted a fastening 80 device G in the form of the figure 8 for attachment of a watch but any other form of fastening device may be attached to the ends of the end bottom links.

Each of the top and bottom links C, D, is positioned within the ordinary link A, one 85 above, and the other below, the wall B thereof, their respective opposite ends extending beyond the ends of the link A, as shown in Figure 1. In order to allow the outer edges of the bars, forming the sides of the links 90 C and D, to lie substantially flush with the outer side edges of the link A, the latter is formed with two recesses in its width, at one end, in which the sides of link C are housed and are adapted to slide, and with 95 two similar recesses at its other end in which the sides of link D are housed and are adapted to slide. To further secure the links C, D in the link A and prevent any side movement I turn over or form a bezel H along 100 the inside edges of links A to hold the links C, D within the link A.

Within each link C, D I position a spring I which has a bearing against one end of the link A and against one end of the link 105 C or D.

With regard to the two central links A¹ (see Figures 6, 8 and 9) I form the top slid-

ing links C plain and connect them together by a ring J and to enable a proper working of the bracelet the top sliding links C on each side of the centre links A¹, A¹, are arranged so that the hinge joint E is positioned at the end farthest from the centre links A¹, A¹.

The sliding links D are connected to the hinge joint E somewhat loosely so that the bracelet can be folded or curved inwardly to allow the bracelet to be manipulated.

For extra wide bracelets the sliding links C, D may be made with division strips K of any desired number with a spring I positioned between each as will be understood from Figure 7.

By this invention I can obtain an expansion of about three quarters of the length of the bracelet or belt a feature not attainable by other similar constructions of bracelet or belt.

I claim:

1. A spring controlled expanding bracelet, belt or the like, comprising a series of units each of said units consisting of a hollow link formed of strips connected together at their ends and open along their sides, a division wall between said strips forming housings for separate springs, an upper closed link having one end passing through the upper of said housings, a spring located between one end of said upper housing and one end of said upper link, a lower closed link having one end passing through the lower of said housings, a spring located between one end of said lower housing and one end of said lower link, in combination with connecting links adapted to connect the upper link of one unit with the lower link of an adjacent unit, for the purposes set forth.

2. A spring controlled expanding bracelet, belt or the like, comprising a series of units each of said units consisting of a main link formed of strips connected together at their ends and open along their sides, a division wall disposed longitudinally between said strips and forming two housings for separate springs, an upper sliding link extending through one of said housings at one end, a spring located in said upper housing and bearing at one end against one end of said upper housing and at the opposite end against the end of the upper sliding link extending through said housing, a lower sliding link extending through the other of said housings at one end, a spring located in said lower housing and adapted to bear at one end against one end of said lower housing and at the opposite end against the end of the lower sliding link passing through said lower housing, and connecting links between the upper sliding link of one unit and the lower sliding link of an adjacent unit, for the purposes set forth.

3. A spring controlled expanding bracelet,

belt or the like, comprising a series of units each of said units consisting of a main link formed of strips connected together at their ends and open along their sides, a division wall disposed longitudinally between said strips and forming two housings for separate springs, an upper sliding link extending through one of said housings at one end, a spring located in said upper housing and bearing at one end against one end of said upper housing and at the opposite end against the end of the upper sliding link extending through said housing, a lower sliding link extending through the other of said housings at one end, a spring located in said lower housing and adapted to bear at one end against one end of said lower housing and at the opposite end against the end of the lower sliding link passing through said lower housing, and connecting links between the upper sliding link of one unit and the lower sliding link of an adjacent unit, said connecting links being rigidly connected to one of said sliding links and pivotally connected to the other, for the purposes set forth.

4. A spring controlled expanding bracelet, belt or the like comprising a series of units connected together end to end, each of said units consisting of a main link formed of strips connected together at their ends and open along their sides, a division wall disposed longitudinally between said strips to form housings for separate springs, an upper sliding link having one end passing through the upper of said housings a spring located in said upper housing and located between one end thereof and one end of the upper sliding link, a lower sliding link having one end passing through the lower of said housings, a spring in said lower housing and located between one end thereof and one end of the lower sliding link, each of said sliding links being mounted to slide longitudinally in opposite directions with respect to said main link, guiding means on said main link for guiding each sliding link in its movement, and connecting links adapted to connect the upper sliding link of one unit to the lower sliding link of an adjacent unit, for the purposes set forth.

5. A spring controlled expanding bracelet, belt or the like comprising a series of units connected together end to end, each of said units consisting of a main link formed of strips connected together at their ends and open along their sides, a division wall disposed longitudinally between said strips to form housings for separate springs, an upper sliding link having one end passing through the upper of said housings a spring located in said upper housing and located between one end thereof and one end of the upper sliding link, a lower sliding link having one end passing through the lower of said housings, a spring in said lower housing and located between one end thereof and one end of the lower sliding link, each of said sliding links being mounted to slide longitudinally in opposite directions with respect to said main link, guiding means on said main link for guiding each sliding link in its movement, and connecting links adapted to connect the upper sliding link of one unit to the lower sliding link of an adjacent unit, for the purposes set forth.

said housings, a spring in said lower housing and located between one end thereof and one end of the lower sliding link, the main link being provided along its longitudinal sides with turned over edges adapted to retain and guide each of said sliding links during its sliding movement, and connecting

links between the upper sliding link of one unit and the lower sliding link of an adjacent unit, for the purposes set forth.

GEORGE WILLIAM HARRISON.
